UNITED STATES PATENT OFFICE.

NEWELL F. RESSEGUIE, OF FREDERICK, SOUTH DAKOTA.

CAR-COUPING.

No. 929,879.

Specification of Letters Patent.

Patented Aug. 3, 1909.

Application filed April 19, 1906. Serial No. 312,699.

To all whom it may concern:

Be it known that I, NEWELL F. RESSEGUIE, a citizen of the United States, and resident of Frederick, in the county of Brown and State of South Dakota, have invented certain new and useful Improvements in Car-Couplers, of which the following is a specification.

My invention relates to improvements in car couplers and consists of the features of construction and combination hereinafter particularly described and claimed.

In the accompanying drawings forming part of this specification, Figure 1 is a vertical section of a pair of co-operating drawheads taken on line $x-x$ of Fig. 3, showing the locked couplers partly in side elevation and partly in section, Fig. 2 is a side view of the drawheads, Fig. 3 is a horizontal section of the drawheads on line $y-y$ of Fig. 2, showing the locked couplers in plan, and Fig. 4 is a perspective view of one coupler alone, with the ball and arm separated from the rest of the coupler.

In the drawings A—A represents the drawheads of two cars (not shown) to be coupled together.

Each coupler comprises a grapples pivotally supported at its hub end F within the drawhead by means of a horizontal pin G. Also supported upon each pin G is a lever H shaped to interlock with the adjacent end of the grapples and carrying upon its lower end a weight C. Each lever H extends through a slot I in the bottom of the drawhead. Each grapples carries at its free end a cam B supported between the arms K. The cams B are heart-shaped as shown in drawings permitting them to slide past each other when the drawheads come together and to

drop into the openings between the arms K. It will be evident that the grapples will interlock from either side *i. e.* one grapples can pass either over or under the other grapples and interlock. Thus variations in the height of the drawheads is compensated for.

D represents a rod extending upwardly from each grapples through the top of the drawhead, whereby the grapples may be raised by hand.

In operation with the coupler members connected as shown in Fig. 1 it will be evident that the right hand weight will hold the attached grapples in interlocking engagement with the other grapples and that the bottom of the drawheads serve as a stop to limit the downward movement of the left hand grapples. In other words the weight of whichever grapples is above will hold the grapples interlocked.

The simplicity and advantage of the construction shown will be apparent.

I claim—

In a car coupler, the combination with a drawhead, of a grapples pivotally mounted therein and provided adjacent its forward end with an opening to receive the grapples of an opposing coupler, a cam arranged at the forward end of the grapples in advance of said opening and projecting at both the top and bottom of the grapples, and a depending counterbalance arranged in said drawhead and projecting through the bottom of the latter, said counterbalance having an interfitting engagement with said grapples.

NEWELL F. RESSEGUIE.
